EMIL S. GRAFENSTATT, OF LOS ANGELES, CALIFORNIA

DEEP-WELL PUMP

Application filed October 18, 1927. Serial No. 226,933.

This invention relates to deep well pumps, and the main object is to provide an improved type of pump adapted to be operated by a pressure element, and so arranged for producing a substantially continuous discharge of the well fluid by reason of the fact that fluid is discharged on both the up and down strokes of the pump plunger.

In the consideration of my present invention, attention is called to my pending application for patent for deep well pumps filed March 10, 1926; Serial Number 93,576, compared with which the present invention embodies material improvements in structure, operation and utility.

Another object is to provide a deep well pump embodying a mechanism which may be readily assembled and disassembled, which will be free from unnecessary parts and extremely simple in operation.

In my said pending application for patent, and in other types of deep well pumps, means was employed for providing a pressure zone between the pump barrel and the well casing for effecting the operation of the pump, whereas in my present invention it is an object to provide a self-contained pump exclusive of the pressure zone or chamber, and adapted to be connected with a pressure mechanism above the surface of the ground, so that the entire pump mechanism may be positioned at a greater depth in the well casing and preferably within the perforated portion of said casing.

In my former type of pump, as well as in other pumps such was impossible, due to the fact that a pressure zone was of necessity maintained in the well casing and around the pump barrel. The structure embodied in the present invention being self-contained as to all of its elements, facilitates the insertion and withdrawal of the pump bodily.

A further object is to provide means whereby the flow pipe with the attendant valves may be lowered into the central casing and into operative relationship with the pump barrel after the pumping mechanism has been properly positioned in the well.

A more detailed statement of objects of

the present invention will be made as the description of my invention progresses.

In the accompanying drawings I have shown a preferred embodiment of my invention, subject to modification within the scope 55 of the appended claims without departing from the spirit thereof.

In said drawings:

Fig. 1 is a sectional elevation, in perspective, of a pump embodying my improvements and dis-associated from the well casing. In this view the relation of the several parts of the pump is such that the pressure is applied to the lower side of the power head during the upward movement of the 65 plunger.

Fig. 2 is a fragmentary sectional elevation of the upper portion of the pump, showing the flow pipe and the check and head valves immediately above the structure 70 shown in Fig. 1.

Fig. 3 is a transverse section of the pump on line 3—3 of Fig. 2.

Figs. 4 and 5 are transverse sections of the pump, respectively, on lines 4—4 and 75 5—5 of Fig. 1.

Fig. 6 is a slightly enlarged fragmentary sectional elevation of the upper portion of the pump shown in Fig. 1, with the power head and control valve shown in positions 80 such elements assume at the initiation of the up stroke of a plunger.

Fig. 7 is a similar sectional elevation of the same, in which the power head and control valve are shown at their uppermost 85 positions within the pump barrel, in readiness for an ensuing down stroke of the plunger.

Fig. 8 is a sectional elevation of a well, showing connections above the ground with 90 a pressure pump and storage tank, by means of which pressure is maintained in the pump for the operation of the pump, and contents of the well are stored for further disposition.

Referring first to Fig. 8, W represents the usual well casing which extends to a point above the ground and is provided with a head W' thereon; C represents a pump casing which may be fitted into the central 100

portion 1 of the well casing head W', and provided with an inlet 2 arranged for connection with a pipe 3 which leads to and is connected with the exhaust 4 of a pressure pump 5. F represents a flow pipe which extends through a portion 6 of the casing head W' and through a packing gland 7. The upper end of the flow pipe F is adapted to be connected by means of a pipe 8 with a storage tank 9. Said tank and the pressure pump 5 may be connected by means of a pipe 10.

Thus a pressure zone is provided within the pump casing C and around the flow pipe F, while the contents of the well are discharged through the flow pipe F and pipe 8 into tank 9.

The pressure pump 5 draws the fluid from the tank 9 through the pipe 10, and discharges it through pipe 3 into the pressure zone for effecting the operation of the pump as hereinafter described.

Briefly described, the pump proper includes a barrel which is composed of aligned sections B and B', which are screwed together at 11. The upper section B is attached to the lower end of the pump casing C, and the lower end of the barrel section B' is provided with a reduced tubular extension b which is screwed to the end of the section at 12.

The barrel is provided with tubular liners A and A' which have correspondingly beveled and closely fitting ends 13, providing a leak-proof joint.

Said liners form cylinders in which a power head D and a control valve E reciprocate.

The upper portion of the barrel section B is provided with a liner a which telescopes into and rests upon the upper end of the liner section A, as shown in Fig. 1, and slidably receives the head G of a hollow stem plunger g. This hollow stem plunger is threaded at its lower end into a piston H which operates in a liner a' in the lower section B' of the barrel.

Said piston has upwardly and downwardly extended hollow stems H' and h, respectively, and the stem h is slidably held in a liner h' which is supported in the lower section b of the barrel. The liner a' rests upon a removable collar b' which is threaded into the lower end of section B' of the barrel.

The upper section B of the barrel is provided with a longitudinal passage 14 of arcuate cross section, which communicates at its upper end with the chamber 15 in the upper end 16 of the barrel, which is adapted to be screw connected with the pump casing C, so that pressure from the pressure mechanism above the ground may be maintained in the passage 14.

Said passage 14 extends downwardly into the section B to a point above and is closed

at its lower end by means of an arcuate rib 17 which is positioned below the lowermost extreme of action of the control valve E. Diametrically opposite the passage 14 in the barrel section B, a similar passage 18 is provided which terminates above and is closed by an arcuate rib 19 positioned near the upper end of the control valve E. The passage 14 is continuously employed as a pressure chamber, while the passage 18 is continuously employed as an exhaust chamber.

Below the rib 19 a passage 20 is provided, which conforms substantially in cross section to the passage 18 and is aligned therewith, and is in communication below the plane of the rib 17 with a circular passage 21. The circular passage 21 terminates above a shoulder 22 in the lower portion of barrel section B' and serves alternately as a pressure and exhaust chamber.

Said passage is in communication with the chamber 23 in the liner section a' below the piston H, by means of one or more ports 24 formed in said liner section, so that pressure from the passage 21 may be applied to the lower end of the piston H for moving the piston and the plunger head G upwardly, and for the purpose of exhausting the fluid from the chamber 23 when said piston and plunger move downwardly.

It will be noted that the upper end of the liner a' telescopes the lower end of the liner A' substantially in the plane of the junction between the barrel sections B and B', providing a chamber 25 within the liners A' and a' and between the upper end of piston H and the lower end of control valve E.

Communication is established between the chamber 25 and the pressure zone 14 by means of one or more ports 26 formed in the liner section A' at a point below the control valve E.

The power head D has annular end portions D' and d, separated therefrom by waist portions 27 and 27', respectively, which are of substantially smaller diameter than the bore of the liner sections A and A' thus providing chambers 28 and 28' intermediate the power head.

The power head is slidably mounted on the plunger stem g and has a depending sleeve d' from the lower end thereof, embracing said plunger stem, on which the control valve E is slidably mounted for differential operation with respect to the power head.

The lower end of the sleeve d' of the power head carries a collar 29 which is held thereon by means of a split ring 30 adapted to seat in correspondingly formed grooves on the interior of the collar and the exterior of the sleeve, as shown in Fig. 6.

It will be observed by reference to Fig. 6 particularly, that a chamber 31 is provided above the portion D' of the power head and

above the head G of the plunger, within the liner section A. Said chamber is of substantially greater area than chamber 32 in said liner, which is formed between the portions D' and D of the power head around the waist 27 thereof.

The upper portion of the liner A is provided with a plurality of peripheral ports 33, 33, which register with an opening 34 of substantial area formed in the inner wall 35 of barrel section B, for affording communication between the chamber 31 and the pressure zone 14. Chamber 32 also communicates with the pressure zone 14 by means of ports 36 formed in the inner wall of the barrel section B and in the liner A.

Intermediate the power head sections D and d and around the waist portion 27' a chamber 37 is provided in the liner section A', which is of substantially less area than the chamber 32. It will be observed in this connection that when the power head reciprocates in the liners A and A', the chambers 32 and 37 will change positions.

For instance, as the power head D moves upwardly in the liner A, the port 36 will be closed while a port 38 formed in the lower portion of liner A and the inner wall 35 of the barrel will be opened. Thus the chambers 32 and 37 will be alternately open and closed to communication with the pressure zone 14 during the reciprocation of the power head.

As shown in Fig. 6, the power head D is at rest at its lowermost extreme of action, with the lower beveled edge of the portion D resting upon the upper beveled end of the lowermost liner section A'. When the power head is so positioned the valve E is in abutting position with the power head, as shown in Fig. 6.

The exhaust chamber 18 communicates at its lower end with an annular chamber 39 and with the valve chamber 40 within the liner section A by means of one or more ports 41 formed in the periphery of the liner. The movement of the valve E serves to open and close said ports when the upper end portion E' thereof is moved upwardly and downwardly during the operation of the pump.

The control valve has a lower portion e spaced from the portion E' by means of a central waist portion e' around which a chamber 42 is formed within the liner section A'. The upper portion of chamber 21 terminates in an annular chamber 43 which communicates with the chamber 42 by means of one or more ports 44.

Said chamber 42 also communicates with the pressure zone 14 by means of one or more ports 45 formed in the liner A' which are adapted to be opened and closed by means of the lower portion e of the valve.

The stem d' of the power head has a port

46 therein immediately below the portion d. The upper end of the control valve is provided with a plurality of abutments 47 for engagement with the lower end of the power head, so as to provide an opening between the valve and power head in registration with the port 46, when the valve and power head are in abutting relation, thus permitting the leakage or bleeding of the pressure between these elements, as more particularly described hereinafter.

Other ports 48 are provided in the liner A' for affording communication between the chamber 43 and the arcuate passage 21. Preferably a plurality of the ports 45 are provided, as shown in Fig. 6, around the wall of the liner A', so that certain of said ports will communicate with a peripheral passage 49 formed in the exterior of the liner A'. The passage 49 communicates with the interior of the liners below the portion e of the control valve by means of a port 50.

Ports 51 and 52 are provided in the inner wall 35 of the barrel B, and similar ports are provided in the liners A and A', respectively, which register with said ports for affording communication between the interior of the liner and the exhaust passage 18 at different points.

The head of the plunger G is provided with a ball valve I within a cage i, which has a hollow tapered nipple 53 held in the upper end of the plunger, as shown in Fig. 1. The head E of the plunger and valve cage or body i reciprocate within the liner a. The upper end of liner a has an enlargement 54 which rests upon a shoulder 55 formed internally of the wall 35 of barrel B.

It will be noted by reference to Fig. 2 that the inner wall 35 of the barrel terminates at a point slightly below the upper end 16 of the barrel, and said wall has a counter-bore 56 which receives a sleeve 57 above the upper end of the liner a. Said sleeve has a tapered bore 58 to receive and hold a correspondingly tapered portion 59 of a valve body j, in which a head valve J is positioned.

The chamber 60 of the valve body j communicates with the chamber 61 of the liner a by means of an inlet 62 and the opposite end of the valve body has an outlet 63 which communicates with the chamber 64 of a check valve k, which carries a valve K 120 therein.

The valves J and K are of usual form and are aligned with the pump mechanism below, so that the fluid from the well may be discharged therethrough into the flow pipe 125 F, which is adapted to be threaded into the upper portion 65 of the valve body k.

In operation, the pump mechanism shown and described herein is adapted to be submerged in the well fluid within the casing 130

W, and due to the particular characteristics of structure shown, the pump mechanism may be positioned at a lower plane in the well than in the type of pump shown in 5 my pending application for patent hereinbefore described.

The lower section of the well casing is usually perforated to permit the flowing of 10 the oil from the sands into the casing. This type of mechanism may be positioned in the perforated section of casing.

When the pumping mechanism above the ground is connected with the pump, as 15 shown in Fig. 8, the pressure fluid which is employed for operating the pump will fill the pressure chamber 14 which is in communication with chamber 31 in the liner A, above the power head through port 33, with chamber 32 around the waist 27 of the 20 power head through port 36, with chamber 25 in the liner a' above piston H through port 26, below valve section e, with chamber 23 in liner a' below the piston H through 25 pressure zone 14, port 45, chamber 42 around waist of the valve, port 48, passages 20 and 21 and ports 24.

Thus due to the fact that the lower side 30 of piston H has a greater area than the upper side thereof, an upward movement of the plunger is effected. This upward movement will continue until the stem H' of piston H engages the end of sleeve d' of the power head and the collar 29 on said sleeve engages the lower end of the control valve 35 E for moving said valve upwardly until the annular end portion e laps port 45. In this position, due to the differential travel of power head D with relation to valve E, communication between chambers 14 and 32 40 is closed inasmuch as power head D will lap port 36.

Communication between chambers 32 and 45 18 however, is established by the opening of port 51, thus making chamber 32 a low pressure chamber, and, as power head portion d laps port 52 communication is closed between chambers 18 and 37, communication is established between chambers 14 and 37 by the opening of port 38, thereby creating 50 a high pressure zone in chamber 37. The upward movement of power head D and valve E continues until the upper portion D' of the power head reaches a point near the upper end of chamber 31 in liner A.

55 When valve E reaches its uppermost position communication is established between passage 18, port 41, chamber 42, ports 45, passages 20 and 21, port 24, and chamber 23, thereby creating a low pressure area below 60 piston H. Thus the greater pressure on the upper side of piston H will cause a downward movement of said piston and plunger head G. The down stroke will continue until plunger head G engages the upper end 65 of power head D and until the lower end

of said power head engages upper end of valve E and moves said valve downwardly for closing communication between chambers 18 and 42 by valve section E', lapping port 41. In such a position power head D will have closed communication between chambers 37 and 14 by lapping port 38, and communication will have been established between chambers 18 and 37 by the opening of port 52, thereby making 37 a low pressure 70 chamber. 75

Communication between chambers 32 and 18 is closed by section D' lapping port 51, and communication between chamber 32 and 14 is established by opening of port 36, thereby making chamber 32 a high pressure 80 zone. Thus downward movement of power head D and valve E is continued until the lower edge of power head D rests on upper 85 end of liner A', as shown in Fig. 6. Thus, a complete cycle of operation is effected.

As the piston H moves on its up-stroke, the plunger G and its stem g , together with the stems H' and h of the piston, being 90 filled with production fluid from the well, and chamber 61 below the valve J being likewise filled with the fluid, the valve J will be forced upwardly into the position 95 shown in Fig. 2 as the valve I moves upwardly with the plunger, thus discharging the column of fluid above the valve I into the flow pipe F, through the valves J and K.

On the down stroke of the plunger, valve J will seat over and close the port 62, while valve K will remain open due to the pressure 100 from the exhaust chamber 18, which discharges through port 66 and valve bodies j and k into flow pipe F. On said downward movement of the plunger, the valve I will open to admit from the interior plunger 105 g into the chamber 61 of the liner a .

Thus it will be noted that while the well fluid is discharged only on the up stroke of the plunger, and the down stroke of the plunger effects a displacement of the pressure fluid, pressure will be created in the flow pipe on both the up and down strokes so as to effect a substantially continuous flow of fluid from the well pump to the outlet.

The flow of the oil from the well sands is substantially the same on the up and down stroke, for the reason that on the up stroke of the plunger a volume of fluid from the well, proportionate to the area of the piston stem h is moved upwardly with the plunger, and as the plunger moves downwardly, due to the fact that the head G of the plunger is of substantially greater area than that of the piston stem h , a volume of fluid is moved upwardly through the plunger to compensate for the difference in area. The column of fluid in the flow pipe is sustained on the valve J when the pressure is relieved from 115 120 125 130

below and within the chamber 61 of the liner *a*.

It will be observed that I have provided a simplified pump, by means of which the production from the well is discharged in a direct path from the well to the flow pipe. The arrangement of the power head, and particularly the control valve is such that the valve is not exposed to contact with the sand content of the production fluid.

10 A further important feature and improvement over other pumps consists in the tandem arrangement of the control valve and power head in telescopic relation to the 15 plunger, which also serves as a flow pipe and a direct outlet from the well for the fluid.

These features are important for the reason that the production fluid is not diverted 20 through circuitous ports, passages and chambers and because of this fact a substantial reduction in frictional losses is attained.

What I claim is:

1. A deep well pump comprising a barrel, 25 a pump cylinder therewithin providing separate pressure and exhaust chambers externally of said cylinder, a hollow plunger centrally mounted in said cylinder and adapted to receive the contents of the well, a flow 30 pipe in communication with said cylinder and the interior of said plunger for discharging the contents of the well, a valve mechanism intermediate said plunger and said flow pipe for controlling the out-put of 35 the well, a pressure mechanism connected with said barrel for maintaining pressure externally of the flow pipe and in said pressure chamber, a tandem arranged power head and control valve embracing said 40 plunger, means formed on said power head and said control valve and cooperating with ports formed in said barrel for affording communication between different portions of 45 said cylinder and said pressure and exhaust chambers for alternately applying pressure to opposite ends of said power head, said control valve serving to regulate the application of pressure to said plunger, said plunger, power head and control valve being 50 differentially connected, for the purpose described.

2. A deep well pump including a barrel, a hollow plunger therein, a flow pipe alined and connected with said plunger, a power 55 head slideable on said plunger and within said barrel, a control valve slideable on said power head and within said barrel, a piston on said plunger below said control valve, and a head on said plunger above said power 60 head, separate pressure and exhaust passages in said barrel externally of said power head and control valve, a pressure mechanism connected with said pressure chamber, said exhaust passage connected with said flow 65 pipe, and means formed in the barrel for

applying pressure to opposite ends of said piston and to opposite ends of said power head on alternate strokes of the pump, for regulating and effecting a substantially continuous discharge of fluid from the flow pipe.

3. A deep well pump comprising a barrel having an inner and an outer wall with separate pressure and exhaust passages formed therebetween, said inner wall forming a pump cylinder, a pressure mechanism connected with said pressure chamber, a flow pipe connected with said cylinder, a plunger in said cylinder in communication with and for receiving the contents of the well, a power head in the upper portion of said cylinder and embracing said plunger, and having a tubular stem depending therefrom, a control valve embracing said stem and positioned in said cylinder below said power head, a head on the plunger above the power head, a piston on said plunger below said control valve, and means for applying pressure to opposite ends of said piston and to opposite ends of said power head for reciprocating said plunger, said power head, and said control valve within said cylinder to regulate and effect the discharge of a fluid from said flow pipe.

4. A deep well pump comprising a barrel having an inner and an outer wall with separate pressure and exhaust passages formed therebetween, said inner wall forming a pump cylinder, a pressure mechanism connected with said pressure chamber, a flow pipe connected with said cylinder, a plunger in said cylinder in communication with and for receiving the contents of the well, a power head in the upper portion of said cylinder and embracing said plunger, and having a tubular stem depending therefrom, a control valve embracing said stem and positioned in said cylinder below said power head, a head on the plunger above the power head, a piston on said plunger below said control valve, means for applying pressure to opposite ends of said piston and to opposite ends of said power head for reciprocating said plunger, said power head, said control valve in said cylinder to regulate and effect the discharge of a fluid from said flow pipe, said means including ports for affording communication between said cylinder and said pressure and exhaust chambers, and means for effecting simultaneous and independent movement of said plunger, power head and control valve on opposite strokes of the pump, for the purpose described.

5. A deep well pump comprising a pump casing, a flow pipe centrally mounted in said casing, a barrel connected with said casing and provided with separate pressure and exhaust chambers therein, a pressure mechanism connected with said casing and with said pressure chamber externally of said flow pipe, liners in said barrel forming a pump

- cylinder, a hollow plunger reciprocable in said liners and provided with substantially spaced head and piston portions in the upper portion of the cylinder, said piston having a passage to permit the flow of a liquid therethrough, a control valve reciprocably mounted on a portion of said power head and also embracing said plunger and positioned in the lower portion of said cylinder 5 above said piston, ports connecting said cylinder with said pressure and exhaust chambers, other ports connecting said pressure chamber with the lower portion of the barrels for applying pressure to opposite ends 10 of said piston and opposite portions of said power head for reciprocating said plunger, power head and control valve, alternately in opposite directions to control the discharge 15 of a fluid to and from said flow pipe.
6. A deep well pump including a pump barrel composed of inner and outer pipes providing separate pressure and exhaust chambers therebetween, a flow pipe connected with the inner pipe, a hollow plunger 20 within the inner pipe, a tandem arranged power head and control valve couplet embracing said plunger and reciprocable in the inner pipe, ports being provided for affording communication between said pressure 25 and exhaust chambers and said inner pipe, and means for applying pressure from the pressure chamber to said plunger, power head and control valve for reciprocating said elements independently and together 30 for regulating and effecting a discharge of the well fluid from said flow pipe.
7. A deep well pump comprising a pump casing, a barrel on the lower end thereof provided with an inlet and an outlet for 35 the well fluid, and pressure and exhaust chambers therein, a pump cylinder within the barrel, a hollow plunger movable in said cylinder for discharging the contents of the well therethrough, differentially operable 40 power head and valve means telescoping said plunger and movable in said cylinder, and means affording communication between the pump cylinder and said pressure and exhaust chambers for controlling the operation 45 of said plunger.
8. A deep well pump comprising a pump casing provided with a barrel on the lower end thereof, a cylinder within said barrel, a hollow plunger reciprocably mounted in 50 said cylinder and provided with a head and a piston substantially spaced apart, said plunger having an inlet in direct communication with the well, and an outlet, a flow pipe connected with said cylinder in communication with said outlet, and means in 55 said barrel and intermediate said head and said piston for regulating the application of a pressure element to said plunger for discharging the contents of the well there- 60 through.

9. A deep well pump comprising a pump casing having a flow pipe therein, a barrel attached to the lower end of said casing and provided with a cylinder alined with said flow pipe, a hollow plunger reciprocably mounted in said cylinder and having an inlet at its lower end in communication with the well, and an outlet at its upper end in communication with said flow pipe, a head on the upper end, and a piston near the lower end of said plunger and substantially spaced apart, a power head, and a control valve embracing said plunger between said plunger head and said piston, and means formed in said barrel for regulating the application of a pressure element to said plunger and said power head for discharging the contents of the well through said plunger. 70

10. A deep well pump comprising a pump casing having a flow pipe therein, a barrel attached to the lower end of said casing and provided with a cylinder alined with said flow pipe, a hollow plunger reciprocably mounted in said cylinder and having an inlet at its lower end in communication with the well, and an outlet at its upper end in communication with said flow pipe, a head on the upper end, and a piston near the lower end of said plunger and substantially spaced apart, a power head, and a control valve embracing said plunger between said plunger head and said piston, and means formed in said barrel for regulating the application of a pressure element to said plunger and said power head for discharging the contents of the well through said plunger, said power head and said valve being differentially operable with respect to each other, for the purpose described. 80

11. A deep well pump comprising a pump casing having a flow pipe therein, a barrel attached to the lower end of said casing and provided with a cylinder alined with said flow pipe, a hollow plunger reciprocably mounted in said cylinder and having an inlet at its lower end in communication with the well, and an outlet at its upper end in communication with said flow pipe, a head on the upper end and a piston near the lower end of said plunger and substantially spaced apart, a power head, and a control valve embracing said plunger between said plunger head and said piston, means formed in said barrel for regulating the application of a pressure element to said plunger and said power head for discharging the contents of the well through said plunger, said power head and said valve being differentially operable with respect to each other, means on said plunger permitting the initial movement of the plunger with respect to and adapted to engage and subsequently operate said power head, and means associated with the power head permitting an initial move- 90

130

ment of the power head and adapted to engage and subsequently operate said valve.

12. A deep well pump comprising a pump casing, a flow pipe therein, a pump barrel attached to the lower end of said casing, a cylinder in said barrel alined with said flow pipe, a head valve in the flow pipe, a hollow plunger reciprocable in said cylinder having an inlet at its lower end for receiving the well fluid, and an outlet at its upper end for discharging the same into the flow pipe, a valve at the outlet of said plunger, an intermediate valve between said head valve and said plunger valve cooperating to enable the plunger to elevate the well fluid into the flow pipe, a piston on the lower end of said plunger and differentially operated power head and control valve elements differentially reciprocable in said cylinder with respect to each other and with respect to said plunger, for controlling the application of a pressure fluid to the plunger in the operation of the pump.

13. A deep well pump comprising a pump casing having a flow pipe therein, a pump barrel suspended from said casing, a cylinder in said barrel, a hollow plunger in said cylinder having an inlet for admitting the well fluid thereto, and an outlet for discharging said fluid into said flow pipe, valve means for controlling the flow of fluid from the well to said flow pipe, a piston associated with said plunger, a control valve for regulating the application of a pressure fluid to said piston for moving the plunger in opposite directions, and a power head for effecting the operation of said valve.

14. A deep well pump comprising an inner and an outer pipe, a pump barrel connected with the outer pipe, a pumping mechanism in said barrel, means for connecting a pressure mechanism with the outer pipe, a plunger within the barrel having a piston thereon, a control valve in said barrel selectively associated with passages through the barrel for applying pressure from the outer pipe to opposite portions of said piston, said plunger having an inlet and an outlet for effecting a flow of fluid from the well through said plunger, and a power head differentially associated with and for operating said control valve.

15. A deep well pump comprising a pump casing and a flow pipe therein, a barrel connected with said casing, a plunger in said barrel having a piston thereon, means for connecting a pressure mechanism with said barrel, said plunger having an inlet in communication with the well, and an outlet in communication with said flow pipe, a control valve embracing said plunger for regulating the application of a pressure fluid to opposite sides of said piston for discharging the contents of the well through said plunger, a power head associated with said

control valve and initially operable by said piston and adapted to be subsequently operated by a pressure fluid, for effecting the operation of said control valve.

16. A deep well pump comprising a pump casing, a barrel suspended therefrom, a flow pipe within said casing, and alined with said barrel, a plunger in said barrel having an inlet communicating with the well and an outlet communicating with said flow pipe, a piston associated with said plunger, a control valve for regulating the application of a pressure fluid to opposite ends of and for moving said plunger in opposite directions, and a power head associated with said control valve, means whereby the initial operation of the power head may be effected through the medium of said plunger, and means whereby the subsequent movement of said power head may be pressure operated, and means whereby said power head will initially move independently of and subsequently effect the movement of said control valve.
